DESIGN FOR A GAME BOARD

Ernest Wade Hampton, Artemus, Ky.

Application December 8, 1941, Serial No. 104,539

Term of patent 3½ years

To all whom it may concern:

Be it known that I, Ernest W. Hampton, a citizen of the United States, residing at Artemus, in the county of Knox and State of Kentucky, have invented a new, original, and ornamental Design for a Game Board, of which the following is a specification, reference being had to the accompanying drawing, forming part thereof.

I claim:

The ornamental design for a game board, as shown.

ERNEST WADE HAMPTON,
